UNITED STATES PATENT OFFICE.

RAY J. BERTHOUD, OF SWANTON, OHIO.

WRENCH.

SPECIFICATION forming part of Letters Patent No. 763,590, dated June 28, 1904.

Application filed January 21, 1903. Serial No. 139,903. (No model.)

To all whom it may concern:

Be it known that I, RAY J. BERTHOUD, a citizen of the United States, residing at Swanton, in the county of Fulton and State of Ohio, have invented certain new and useful Improvements in Wrenches; and I do declare the following to be a full, clear, and exact description of the invention, such as will enable others skilled in the art to which it appertains to make and use the same, reference being had to the accompanying drawing, and to the figures of reference marked thereon, which forms a part of this specification.

My invention relates to wrenches for cylindrical objects, and is designed to furnish a cheap, simple, and effective device which is especially well adapted for screwing and unscrewing screw-caps for glass fruit-jars and similar vessels. I attain these objects by means of the devices and arrangement of parts hereinafter described, and shown and illustrated in the single figure of the accompanying drawing, which represents my wrench expanded and ready to be applied to the object to be turned.

In the drawing, 1 is a flexible metal band, preferably of sheet metal, bent in U shape in cross-section, though it may be of wire or of any other suitable cross-sectional form. This band is formed in substantially circular shape with the two ends disconnected from each other and overlapping each other and of such dimension when expanded as to receive loosely the object to be turned. One end of the flexible band is flattened, as shown at 2, and terminates in a thumb-piece 3. The band near its opposite end is flattened on its outer margin, forming a plate, as at 4.

5 is a wrench-handle which in the present example of my invention is stamped from sheet metal, curved in cross-section and at its inner end bifurcated and formed into two parallel plates 6. The plate 4 is pivotally secured between the extremities of the plates 6, as at 7, and the plate 2 is pivotally secured between the plates 6, as at 8.

The operation of my device is as follows: The handle being held in the hand of the operator, with the thumb resting upon the thumb-piece 3, an outward pressure upon the thumb-piece will cause the two ends of the

flexible band to swing upon their pivotal supports 6 7 into expanded position. The band may now be slipped over the screw-cap or other object to be turned or screwed. The thumb being removed from the thumb-piece, the resiliency of the band will cause it to clasp the object which it encircles. Now by moving the outer extremity of the handle shown in the drawing to the right the two 60 ends of the flexible band are moved in opposite directions and the band is caused to tightly clasp and to turn the cap or other object which it embraces. The opposite movement of the handle will in like manner cause the ends of 65 the band to move in opposite directions and to thus expand and release the cap or other object. The device shown in the drawing is arranged and disposed in such manner as to screw a right-handed thread onto its corresponding thread by turning the handle to the right. By reversing the device and moving the handle to the left the opposite result is effected.

If the resiliency of the band is insufficient to 75 cause it to clasp the object to be turned closely enough to act automatically when the handle is moved, a slight pull upon the thumb-piece will instantly obviate this difficulty.

It will be observed that the inner margin of 80 the plate 4 is formed in the arc of a circle and that when the wrench is in operative engagement with the object to be turned such object will be equally clasped by the band in a complete circle.

Having described my invention and its operation, what I claim, and desire to secure by Letters Patent, is—

In a wrench, a band of resilient metal, a handle, a pivot on the handle engaged with the 90 band near one end thereof, another pivot on the handle spaced apart from the first-mentioned pivot and connected to the band near its other end, and a finger-piece secured to said band, adapted for manual manipulation 95 and arranged to expand and contract the band.

In testimony whereof I affix my signature in presence of two witnesses.

RAY J. BERTHOUD.
